UNITED STATES PATENT OFFICE.

ALEXANDER HENDERSON, OF PASSAIC, NEW JERSEY, ASSIGNOR TO MANHATTAN RUBBER MANUFACTURING COMPANY, OF PASSAIC, NEW JERSEY, A CORPORATION OF NEW JERSEY.

DESIGN FOR A MAT.

41,013.

Specification for Design.

Patented Nov. 29, 1910.

Application filed December 24, 1909. Serial No. 534,900. Term of patent 14 years.

To all whom it may concern:

Be it known that I, ALEXANDER HENDERSON, a citizen of the United States, residing at Passaic, in the county of Passaic, State of New Jersey, have invented a new, original, and ornamental Design for Mats, of which the following is a specification, reference being had to the accompanying drawing, forming part thereof.

The figure of the drawing is a plan view of a mat showing my new design.

The mat is formed with a series of parallel ridges or corrugations as shown, to give an effect like moire or watered silk. The light and shadow effects produced by the design

vary, and depend upon the position of the observer or the direction in which the light strikes the mat. The figures of the design as shown are formed by having parallel corrugations of certain portions running at an angle to the parallel corrugations of its adjacent or surrounding portions.

What I claim is:

The ornamental design for a mat as shown and described.

ALEXANDER HENDERSON.
